UNITED STATES PATENT OFFICE.

CHARLES G. ERICSON, OF TORONTO, ONTARIO, CANADA.

RAIL ANCHOR.

Application filed December 3, 1924. Serial No. 753,739.

To all whom it may concern:

Be it known that I, CHARLES G. ERICSON, of the city of Toronto, in the county of York, Province of Ontario, Canada, a subject of the King of Great Britain, have invented certain new and useful Improvements in Rail Anchors, of which the following is a specification.

This invention relates to rail anchors by means of which longitudinal displacement of the railroad rails, commonly called "creeping" may be prevented.

As is now well known to all familiar with the conditions, either direct or contributory, that cause the longitudinal movement of a rail under traffic, one of the outstanding difficulties respecting rail anchors as heretofore constructed has been the means for securing them permanently to the rails at all times. The successful anchor must not only retain its grip on the rail during the period of rest, that is to say, when there is no traffic, but must also have certain compensating reacting qualifications exerting their force during the vertical movement of the rail due to traffic conditions, commonly known as the "wave motion."

Much study and ingenuity have been exercised in providing rail anchors to overcome longitudinal movement of the rails, and devices of this character as heretofore employed divide themselves into three groups: 1st, the strap type, wherein the rail has bolted to it a metal strap which also bears upon or is secured to one of the cross-ties of the railroad bed, as, for instance, shown by the Bonzano Patent, No. 661,101, September 20, 1898; 2nd, the wedge type, wherein the parts of the anchor are held to the rail by a wedge located at one edge of the rail base and embraced by a hook of a cross-member or bar, the other end of which is provided with a smaller hook for engaging the opposite edge of the rail base, as, for instance, shown in the patent to Dorpmuller, No. 791,139, May 30, 1905; 3rd, the spring type, wherein a cross-bar is given a torsional or distinct spring action which asserts itself by a tendency of the cross-bar to assume its original position, as shown, for instance, in Vaughan, No. 897,038, August 25, 1908.

The present invention relates to the wedge type of anchor and comprises in its construction a novel cross-member or yoke and a novel construction of shoe which is engaged by the larger hook of the yoke when the

parts are in service position. Since it is a well-known mechanical law that all metal when given a torsional or distinct twist or continued under spring tension during an extended period gradually takes a permanent set in the direction of the torsion applied or the direction of spring tension to which it is subjected, the present invention aims to provide a rigid construction in the parts of the rail anchor which are normally free from spring stress or tension which by strong frictional engagement between the parts is nevertheless held in its service position to prevent rail creeping. Owing to the rigid character of the anchor of the present invention and the absence of spring torsion or stress in the parts thereof, the anchor may be repeatedly removed from the rail and repeatedly re-applied without deterioration of any of its operative functions.

The various novel features of the present invention and new combination of parts will best be made clear from the following description and the accompanying drawings of one good form thereof.

In the drawings:

Fig. 1 is a perspective view, with the rail in section, showing the anchor of the present invention applied thereto in service position;

Fig. 2 is a perspective view of the shoe which engages one edge of the rail base and has the tie-abutting member;

Fig. 3 is an under-side view of the shoe, showing more particularly the novel construction thereof;

Fig. 4 is a side elevation partly in section of the shoe and yoke separated from the rail and looking in the direction from the rail edge to which the shoe is applied;

Fig. 5 is a section on the line 5—5 of Fig. 7, with the yoke omitted, and showing more particularly the novel provision in the shoe itself for accommodating the rail "wave" during the passage of the load over the rail;

Fig. 6 is an enlarged sectional elevation showing more particularly the yoke and the manner of its initial application to the rail base;

Fig. 7 is a similarly enlarged side elevation showing the yoke and shoe in service position; and

Fig. 8 is a section on the line 8—8 of Fig. 7, with the rail omitted, and showing the strengthening web or upset condition of the small hook at one end of the yoke.

The rail may be of any usual construction and as shown in the present instance comprises the upper wheel engaging portion 1 and base 2 united by the upstanding flange 3 extending between them. Railroad rails as now usually constructed have the bottom surface 4 of the rail base 2 formed substantially in a horizontal plane, viewing the rail in its operating position, and each of the top surfaces 5 of the rail base formed on an incline extending downwardly from the flange 3. It is now, also, the usual practice to support railroad rails upon cross-ties 6, as indicated in Fig. 1, and such cross-ties may be formed of suitable material, such as wood or metal, as preferred, the rail itself being secured thereto by means such as the usual spikes or other securing devices.

In accordance with the present invention, the anchor comprises two parts, one a shoe having upper and lower jaws for embracing one edge of a rail base and an abutment for engaging the cross-tie, and a yoke member having a small hook for engaging one edge of the rail base and a larger hook for engaging about the shoe at the other edge of the rail base and in overhanging relation thereto. Each of these members is of novel construction, and by their combined operation in service position absolutely prevent rail creeping, while at the same time providing for a secure engagement of the anchor to the rail base both during its periods of rest and during traffic conditions and vibrations due to the passing load.

The shoe comprises an upper jaw and a lower jaw which engage the edge of the rail base between them. The upper jaw 36 has its upper surface flat or parallel to the lower surface of the rail base, as indicated in Fig. 7, while the under surface of the upper jaw is formed substantially on the incline of the upper surface of the rail base, as indicated at 7, Fig. 7. At the entering end portion of the upper jaw 36 is a downwardly inclined surface 8 which serves as a preliminary guide for the assembling of the yoke upon the rail by hand. In other words, the short incline or bevel 8 formed on the end portion of the shoe acts to permit ready assembly of a yoke and shoe in their preliminary position on the rail by hand, but has no other function, because when the yoke and shoe have been thus assembled by hand, the yoke is driven on the shoe in the direction of the shoe length, or longitudinally of the rail, into service position, whereas the yoke member, as will hereafter more fully appear, rests solely upon the flat top surface of the upper jaw 36 of the shoe.

The lower jaw of the shoe is formed by two projections which extend inwardly to

engage the under surface of the rail base, and are separated by a space to accommodate the rail wave during the passage of the load. One good form of this feature of the invention is illustrated clearly in Figs. 2, 3, 4 and 5, wherein the lower jaw is shown as provided with a projection 9 at one end thereof, and a projection 10 at the abutment end, the two portions 9 and 10 being separated by a space between them. Thus the shoe has a continuous upper jaw which rests upon the upper surface of the rail base, as hereinbefore described, and a non-continuous lower jaw which bears upon the under surface of the rail base and preferably formed as a projection at each end of the lower jaw, with the result that during the wave motion of the rail under the conditions of traffic, the rail wave may take place as indicated by the dotted lines in Fig. 5, between the projections 9 and 10, forming the lower jaw. This feature of the invention is important, because during traffic conditions the jaws of the shoe are not distorted nor disturbed in their relation with the base flange of the rail, due either to the rail wave or vibrations incident to passing traffic. In other words, the rail wave, as indicated by dotted lines in Fig. 5, may take place between the projections 9 and 10 of the lower jaw without disturbing the relation of either jaw with the rail base flange.

The shoe is provided with a wedge 11 which extends longitudinally of the shoe at the back thereof, as indicated more clearly in Fig. 3, and the inner edge 12 of the upper jaw is formed parallel to the longitudinal dimension or element of the wedge 11. The wedge 11 is eccentric to the shoe, that is, while it extends longitudinally of the shoe, its central element is located at a point below the horizontal plane passed centrally through the rail base, and the zone of the eccentric wedge provides a bearing for the inner surface of the larger hook of the yoke, as will hereinafter more fully appear, which extends upwardly and downwardly from a point below the horizontal plane passed centrally through the rail base. This feature of the invention is best indicated in Fig. 7 wherein the line 13-13 indicates a horizontal plane passed centrally through the rail base 2, while the line 14-14 indicates a horizontal plane passed through the central element of the wedge which, as will be noted, is below the line 13-13 and yet above the horizontal plane of the under surface of the rail base.

Thus the wedge is eccentrically related to the shoe and to the rail base and affords a bearing surface, indicated by the line 15, Fig. 7, for the inner surface of the larger hook of the yoke, as will hereafter appear, to cause a downward stress on the rigid yoke

- in the latter's travel to operative position, resulting in a tight frictional engagement against the upper surface of the upper jaw of the shoe; and second, the eccentric arrangement of the wedge prevents any condition which would tend to force the shank of the yoke, as will later appear, away from and out of frictional contact against the under surface of the rail base.
- 5 At the cross-tie end of the shoe there is provided an abutment 16 having its inner side edge 17 in a vertical plane passed through the innermost edges of the shoe jaws, and its opposite or outer edge 18 offset relative to the back of the shoe and the eccentric wedge. By so constructing the abutment member, a stiffening rib or web 19 is provided which is symmetrically disposed relative to the side edges of the abutment, and the metal of which rib or web merges into and in alinement with the back of the shoe, as indicated in Figs. 2 and 3. In other words, the metal of the strengthening rib or web 19 may be centrally disposed 25 with relation to the abutment and yet have increased strengthening effect thereupon by merging the metal of the rib or web into the solid metal of the shoe at the back or eccentric wedge portion thereof.
- 30 Hereinbefore the lower jaw of the shoe has been described as comprising projecting portions, as shown, formed at each end of the shoe with a space between, and in order to provide increasing strengthening effect of 35 the shoe between the projecting portions 9 and 10 of the lower jaw, the present invention provides a bridge of metal 20 between the projections 9 and 10 which may rest directly upon the edge of the rail base when 40 the shoe is in operative position. This arrangement of the abutment and the strengthening rib or web 19 merging into the solid metal at the back of the shoe adds greatly to the strength of the abutment portion of 45 the shoe, and yet enables the weight of the shoe as a whole to be minimized. In carrying this feature of the invention into effect, also, the projection 10 of the lower jaw is curved outwardly from the abutment 16, as 50 indicated in Fig. 3, at 21, to thereby add materially to the strength of both the abutment 16 and the projection portion 10 of the under jaw.
- 55 In the present instance of the invention, the shoe has a portion 22 beyond the working portion of the flat surface 6' of the shoe removed to thereby minimize the metal contents of the shoe as a whole and yet not detract from its strength and durability under service conditions.
- 60 The shoe is preferably formed of malleable metal, while the yoke member is formed of a harder metal, preferably steel, the construction being such that when the parts are 65 in service position, the harder metal of the
- yoke may take a firm frictional grip into the softer metal of the shoe to thereby prevent disturbance of the relation of the parts during vibrations incident to traffic and other conditions. The yoke member itself is of 70 novel construction and in co-operative relation with the softer metal of the shoe not only insures that the parts shall remain in service or working position during rest, but that the relation of the parts, due to the firm 75 frictional grip incident to their construction, shall not be disturbed during vibrations incident to the passing traffic.
- The yoke member 23 is of rigid and rugged construction and formed of steel. At 80 one end the yoke member 23 is provided with a smaller hook 24 to engage one edge of the rail base, and at its opposite end is provided with a larger hook 25 to engage about the shoe and eccentric wedge, the end portion of the larger hook remaining in overhanging relation with the rail base when the parts are in working position.
- In order to increase the rugged and rigid character of the yoke 23, the dimensions 85 thereof in the plane passed through the hooks and body portion of the yoke are increased over the dimensions of the yoke in a plane at right angles thereto. In other words, as indicated in Fig. 4, the vertical 90 dimension of the yoke member, as indicated by the line *a* of Fig. 4, when the yoke member is in operative position, is greater than the dimension *b*, at right angles thereto, the result being that the yoke presents a substantially unyielding character and is sufficiently rugged to coat with the softer metal shoe to accommodate itself to the vibrations under passing loads.
- The smaller hook 24 at one end of the yoke has its inner engaging surface 26 at an angle less than the angle representing the upper inclination of the upper surface of the rail base, as indicated by the line 27, Figs. 6 and 7, with the result that when the yoke is forced to service position, the inclined surface 26 climbing up the steeper inclined surface 5 of the rail base tends to draw the shank portion of the yoke 23, as at 28, into closer frictional engagement 100 against the under surface of the rail base. This increased frictional hold between the shank portion of the yoke and the under surface of the rail base progressively increases as the small hook climbs the incline 105 5, so that when the parts are finally moved to service or working position, the inclined surface 26 of the small hook may bite into the metal of the rail base and produce a non-disturbable strong frictional grip between 110 the parts.
- The short hook 24 is not simply bent to position, but, on the other hand, it is upset and reinforced, in order to enable that portion of the yoke to accept the stresses im- 115
- 120
- 125
- 130

posed upon it in the application of the yoke to its working position and later to withstand the impact of the vertical movement of the rail induced by the wheel loads passing over the point where the anchor is secured. In thus upsetting the small hook 24, reinforcing flanges 29, one at each side of the small hook, are produced, and these may extend to the outer surface of the small hook, as indicated at 30, with the result that all torsional spring action of the small hook is prevented and the hook itself, by its rigidity, is enabled to withstand the stresses and vibrations due to service conditions.

The larger hook 25 at the other end of the yoke is of novel formation and is so constructed and arranged that when the yoke is in service position, as indicated in Fig. 7, the end portion of the large hook 25 will rest upon the top horizontal surface of the upper jaw of the shoe and be forced into close frictional engagement therewith by the eccentric wedge as the yoke is forced thereover.

The larger hook 25 has the inner surface 31 of the end 32 inclined downwardly and inwardly towards the upwardly extending flange 5 of the rail and has also its inner surface in a zone represented by the line 15, Fig. 7, formed to bear upon the eccentric wedge 11. The portion of the inner surface of the hook 25 between the end bearing 31 and the zone 15 is so shaped, as indicated in Fig. 7 at 33, to provide that the inner surface of the hook 25 will bear only upon the top horizontal surface of the upper jaw of the shoe and along the zone 15 of the eccentric wedge, with the result that when the parts are driven to working position, there will be a downward stress on the rigid yoke jaw, resulting in a tighter frictional engagement against the surface of the upper jaw of the shoe, while at the same time there will be no upward movement of the large hook as a whole due to the engagement of the rounded inner surface of the hook 25 along the surface of the longitudinally extending eccentric wedge. The result is that the yoke member 23 is not sprung or distorted or placed under spring tension, nor is it bent about the under surface of the rail base as a center, but remains intact, and by the strong frictional grip between the small hook and rail base on the one hand and the larger hook upon the eccentric shoe on the other hand, the anchor as a whole is substantially rigid in character and retains its capacity to discharge its function to prevent rail creeping, regardless of the intermittency of its periods of rest and activity. Moreover, since the parts of the anchor are not subjected to a continuing distortion or spring action, which would be liable to render the

parts unserviceable for repeated application under the laws of the fatigue of metals, the present anchor may be repeatedly taken off and applied to rails, and yet discharge its full anti-creeping function.

Another important feature in accordance with the present invention is the construction of the larger hook of the yoke, which enables the yoke to be readily assembled with the shoe on a rail by hand, and then moved to its service position, and to there be retained indefinitely and permanently. To this end the leading edge portion of the larger hook 25 of the yoke member is rounded, as indicated at 34, Fig. 4, while the other or trailing edge 35 of the hook is more abrupt or sharp and constitutes a biting edge. When, therefore, the yoke is applied by hand to the rail and shoe, the leading rounded edge portion 34 of the larger hook will readily move over the entering inclined portion 8 of the shoe and permit the parts to be assembled in hanging relation upon the rail by manual effort, or by hand, it being understood that the inclined portion of the bevel 8 of the shoe has no other function than to direct the parts to engaging position. When the yoke has been thus assembled upon the rail and shoe by hand and is thereafter driven into working position—which commences only after the large hook has been engaged with the flat top surface of the upper jaw of the shoe—the biting edge or trailing edge 35 of the larger jaw will be forced into intimate contact with the upper flat surface 6' of the jaw 36 of the shoe by the downward stress placed upon it by the eccentric wedge and retrograde movement of the yoke will be prevented by the strong frictional engagement between the softer metal shoe and the harder metal of the yoke.

Since one of the purposes of the present invention is to provide a yoke member of distinct rigidity, as contrasted with a spring-tension cross-bar or member, the yoke is provided with a harder surface or skin, which may be produced conveniently during the operation of manufacture by heat treating the yoke and while hot subjecting it to a quenching operation at suitable temperature, whereby the surface of the steel yoke is hardened without rendering the yoke as a whole brittle. Thus the yoke is tough and strong and is given a hard surface, which particularly asserts itself in the gripping action of the yoke upon the somewhat softer metal of the shoe.

A rail anchor constructed in accordance with the present invention does not utilize any distinct lock for holding the parts in anti-creeping position or in the assembling of the parts upon the rail base, nor is there any torsional or distinct spring action, but, on the contrary, the anchor presents a rigid

structure and the cooperation of the parts is such that the anchor will remain in service position to prevent rail creeping during conditions incident to its periods of rest and 5 also under the vibrations and wave motion of the rail during traffic. The absence of a distinct spring action in the parts of the anchor avoids the permanent set that frequently occurs in anchors where torsional 10 or other spring condition is relied upon either to assemble the anchor upon the rail or to be asserted during the discharge of its anti-creeping function.

What is claimed is:

15 1. In a rail anchor, the combination of a metal shoe adapted to engage one edge of a rail base and having a longitudinally extending wedge portion, a yoke formed of harder metal than the shoe adapted to span the rail base and provided with a small hook for engagement with one edge of the rail base, a larger hook at the other end of the yoke embracing the shoe and having the free end of the hard metal hook bearing 25 upon the upper surface of the softer metal shoe to create between the hard metal of the yoke and softer metal of the shoe a frictional grip when the parts are forced to working position that remains undisturbed 30 by vibration of passing traffic.

2. In a rail anchor, the combination of a shoe having a longitudinally extending wedge portion and formed of malleable iron adapted to embrace one edge of a rail base, a rigid yoke member formed of steel adapted to span the rail base and provided with a small hook to engage over the outer edge of the rail base, and a larger hook to embrace the shoe and bear upon the upper 40 surface thereof in overhanging relation with the rail base, the large hook being provided with an outer skin harder than the malleable iron shoe to engage the softer metal of the shoe when the parts are driven to service 45 position and thereby provide a strong frictional grip between the engaged metals that remains undisturbed by vibrations of passing traffic.

3. In a rail anchor, the combination of a shoe having flanges to embrace the upper and lower surfaces of the rail base between them and having a longitudinally extending eccentric wedge portion, a rigid yoke member adapted to span the rail base and 55 provided with a small hook to engage one edge of the rail base and a larger hook embracing the eccentric wedge portion at the other edge of the rail base, said hook having its end bearing upon the upper surface of the shoe in overhanging relation to the rail base so that the end of the hook may be subjected to stress when forced to service position about the eccentric wedge to cause the shoe and end portion of the large 60 hook to move into firm frictional engage-

ment which remains undisturbed by vibration of passing traffic.

4. In a rail anchor, the combination of a shoe member adapted to embrace one edge of the rail base and provided with a longitudinally extending wedge portion eccentric to the horizontal plane passed centrally through the rail base, a rigid yoke member adapted to span the rail base and provided with a small hook at one end to engage over 70 one edge of the rail base and with a larger hook at the opposite end adapted to embrace the shoe and bear upon it at two separated points, one at the eccentric wedge and the other at the top of the shoe in overhanging relation with the rail base so that the end portion of the hook may be caused to exert a strong frictional grip on the shoe when the parts are forced to working position. 75

5. In a rail anchor, the combination of a shoe adapted to engage one edge of the rail base and having a longitudinally extending wedge portion and a tie abutment, a rigid yoke member adapted to span the rail base 80 and provided with a small hook having the surface which engages the inclined upper surface of the rail base at a less inclination than the latter, a larger hook at the opposite end of the yoke adapted to engage the 85 shoe and wedge so that when driven to working position the small hook will climb up the inclined surface of the rail base and cause the yoke to exert a strong frictional hold on the under surface of the rail base and the end of the larger hook to exert frictional pressure on the top surface of the shoe in overhanging relation to the rail base. 90

6. In a rail anchor, the combination of a shoe having a continuous upper jaw to overlie the upper surface of a rail base and a non-continuous lower jaw constructed and arranged to engage the lower surface of the rail base at points separated longitudinally of the rail base to provide a space for the rail wave, and a yoke having a hook at one end to engage the rail base and a hook at the other end to embrace the shoe. 105

7. In a rail anchor, the combination of a shoe having a continuous upper jaw to engage the upper surface of a rail base and a non-continuous lower jaw adapted to engage the lower surface of the rail base, said lower jaw comprising two separated projecting portions, one at each end of the shoe, to 110 extend under the rail base, and a yoke adapted to engage one edge of the rail base and the shoe at the opposite edge of the rail base. 120

8. In a rail anchor, the combination of a shoe having a wedge portion extending longitudinally thereof and provided with a pair of rail edge embracing jaws, the upper jaw being continuous, and the lower jaw being formed by a projection at each end of the shoe separated by an open space from which 125 130

the metal has been omitted that the wave movement of the rail may take place between the two projections forming the lower jaw of the shoe, and a yoke engaging one edge of the rail base and the shoe at the opposite edge thereof.

9. In a rail anchor, the combination of a shoe having a wedge portion extending longitudinally thereof and provided with a pair of rail edge embracing jaws, the upper jaw being continuous, and the lower jaw being formed of a projection at each end of the shoe separated by an open space from which the metal has been omitted that the wave movement of the rail may take place between the two projections forming the lower jaw of the shoe, a strengthening bridge formed on the shoe between the two projections, and a yoke engaging one edge of the rail base and the shoe at the opposite edge thereof.

10. In a rail anchor, a shoe for engagement with an edge of a rail base, comprising a wedge extending longitudinally along the back of the shoe, an upper jaw adapted to rest upon the top of the rail base flange, a lower jaw formed by a projection at each end of the shoe separated by an open space from which the metal has been omitted, an abutment for engaging a tie, and a stiffening rib extending between the abutment and the wall of metal forming the lower portion of the shoe joining the two projections comprising the lower jaw.

11. In a rail anchor, a shoe comprising a wedge back, jaws integral therewith adapted to embrace the edge of the rail base, a depending abutment member integral with the back and jaws and having its inner side substantially in alignment with the inner edge of the jaws and its outer edge outwardly offset relative to the back of the shoe, and a stiffening rib symmetrically disposed relative to the sides of the abutment and merging into and in alignment with the underside of the back.

12. A rail anchor comprising a shoe adapted to embrace one edge of a rail base and having its back formed as a wedge, a yoke adapted to span the rail base having a hook at one end adapted to engage the other edge of the rail base, and a hook embracing the wedge shoe and overhanging the rail base, the throat of the hook being curved so that the hook engages the wedge shoe only at the back and adjacent its upper inner edge to exert a biting frictional engagement between the upper surface of the shoe and the end of the hook.

13. A rail anchor comprising a shoe adapted to embrace one edge of a rail base and having its back formed as a wedge and having the inner edge of its upper side substantially parallel to the back, a yoke adapted to span the rail base having a hook at one

end adapted to engage the other edge of the rail base, and a hook embracing the wedge and overhanging the rail base, the throat of the hook being curved so that the hook engages the shoe only at the wedge back and adjacent its upper inner edge.

14. A rail anchor comprising a shoe adapted to embrace one edge of a rail base and having its back formed as a wedge and having the inner edge of its upper side substantially parallel to the back, the active upper surface of the shoe being substantially parallel to the under side of the rail base when in position on a rail, and a yoke adapted to span the rail base having a hook at one end adapted to engage the other edge of the rail base, and a hook embracing the wedge shoe with its end engaged with the active upper surface of the shoe overhanging the rail base, the throat of the hook being curved to engage the shoe only at the wedge back.

15. In a rail anchor, the combination of a shoe having upper and lower jaws for embracing the edge of a rail base, a yoke adapted to span the rail base and having a hook to engage one edge of the rail base, a larger hook adapted to embrace the shoe and having its leading side edge rounded to facilitate assembly of the yoke and shoe, and the other or trailing side edge abrupt to bear upon the upper surface of the shoe with a biting frictional hold to prevent relative movement of the shoe and yoke after the parts have been driven to working position.

16. In a rail anchor, the combination of a malleable iron shoe having a longitudinally extending wedge portion and jaws for embracing one edge of the rail base, a rigid yoke having a hook to engage the other side of the rail base, and a larger hook to embrace the shoe the leading side edge of the larger hook being rounded to facilitate assembly of the yoke and shoe to working position and the trailing side edge of the larger hook relatively sharp to engage the malleable iron shoe with a frictional grip and prevent loosening the parts under vibration due to traffic.

17. In a rail anchor the combination of a shoe adapted to embrace one edge of a rail base, a yoke member having a small hook at one end adapted to embrace one edge of the rail base and a larger hook at the other end adapted to embrace the shoe, the metal forming the small hook being upset to increase the cross sectional area in a plane extending from the throat to the back of the hook and thus increase the rigidity and strength of the hook.

18. In a rail anchor, the combination of a shoe having upper and lower jaws for embracing one edge of a rail base, a rigid yoke member having a small hook at one end the metal of which is upset and laterally reinforced to withstand the stress imposed

upon it as it is moved to service position and to withstand later the wave movement of the rail during traffic, a larger hook at the other end of the yoke adapted to embrace the shoe, the rigidity of the yoke at all parts being augmented by greater dimension in the plane passing through the hooks and body of the yoke than at points at right angles thereto.

19. In a rail anchor, the combination of a shoe having jaws for embracing one edge of a rail base and provided with a longitudinally extending eccentric wedge portion at its back the center line of which is below the horizontal plane passed centrally through the rail base, a yoke member having a small hook at one end to engage one edge of the rail base and a larger hook at the other end to embrace the shoe and eccentric wedge so that when moved to service position a downward stress will be exerted on the edge of the larger hook to force it into close frictional engagement with the upper surface of the upper jaw in overhanging relation to the rail base without forcing the body or shank of the yoke from close frictional engagement with the under surface of the rail base.

20. In a rail anchor, the combination of a shoe for engaging one edge of a rail base and provided with a wedge portion extending longitudinally at the back thereof, a steel yoke having a small hook at one end to engage one edge of a rail base and a larger hook at the other end to embrace the

shoe and wedge, the steel yoke being formed with a hardened outer surface to impart increased rigidity to the yoke and effect a holding frictional grip upon the metal of the shoe when the parts are forced to service position on a rail.

21. In a rail anchor, the combination of a shoe for engaging one edge of a rail base and provided with a wedge portion extending longitudinally at the back thereof, a steel yoke having a small hook at one end to engage one edge of a rail base and a larger hook at the other end to embrace the shoe and wedge, with the end of the hook bearing on the surface of the shoe and overhanging the rail base and having the leading side edge rounded and the trailing side edge of the hook sharp, the steel yoke being formed with a hardened outer surface to impart increased rigidity to the yoke and effect a holding frictional grip upon the metal of the shoe when the parts are forced to service position on a rail.

22. In a rail anchor, a shoe having a continuous jaw to engage the upper surface of a rail base, a lower jaw formed by portions of the shoe separated longitudinally of the rail by an open space, a wedge portion extending longitudinally of the shoe, an abutment, and a rib or web of metal extending from the abutment and merging into the continuous metal of the shoe back.

Signed at Toronto, Canada, this 29th day of November, 1924.

CHARLES G. ERICSON.
